UNITED STATES PATENT OFFICE.

EVEN ULLAND, OF MINNEAPOLIS, MINNESOTA.

ROTARY ENGINE.

1,306,238.

Specification of Letters Patent. Patented June 10, 1919.

Application filed February 12, 1918. Serial No. 216,765.

To all whom it may concern:

Be it known that I, EVEN ULLAND, a citizen of the United States, residing at Minneapolis, in the county of Hennepin and State 5 of Minnesota, have invented certain new and useful Improvements in Rotary Engines, of which the following is a specification.

My invention relates to rotary engines and has for its object to provide an engine having 10 two rotary piston heads working in annular piston chambers into which live steam is admitted alternately so that energy will be transmitted in a constant manner.

The full objects and advantages of my invention will appear in connection with the detailed description thereof and are particularly pointed out in the claims.

Referring to the drawings, Figure 1 is a view partly in vertical section taken at about 20 the line 1—1 of Fig. 2 but with the portion at the upper right side a little in front of the line and a portion at the upper left side a little behind this line. Fig. 2 is a view in section on line 2—2 of Fig. 1. Fig. 3 is 25 a view in section on line 3—3 of Fig. 1 but showing the gate raised. Fig. 4 is a view mostly in end elevation with the cam disk removed. Fig. 5 is a rear elevation. Fig. 6 is a sectional detail showing the inlet and 30 outlet passages. Fig. 7 is a view in end elevation showing the cam disk with cam grooves in dotted lines. Fig. 8 is a top view of one of the admission valves. Fig. 9 is a side view of one of the admission valves 35 showing its operating connection. Fig. 10 is a detail showing the annular gasket co-operating with the annular piston. Fig. 11 is a detail view at right angles to Fig. 10. Fig. 12 is a view similar to Fig. 10 showing the gasket 40 held in different manner. Fig. 13 is a view at right angles to Fig. 12. Fig. 14 is a detail of the mechanism connected to one end of the gate. Fig. 15 is an end view of the gate showing the gasket in place. Fig. 16 is a 45 view at right angles to Fig. 15.

In the engine shown in the drawings a duplicate arrangement of the piston chambers, annular pistons and rotary piston heads is provided and engine casting is made 50 in three sections 4, 6 and 8 rigidly secured together in suitable manner, as by bolts 10. The three part casting is formed with a pair of annular piston chambers 12 partly within the intermediate section and partly within 55 the outer sections of the casting. The sections 4, 6 and 8 at their central portions are

spaced apart to form annular passages for the relatively thin annular pistons 14 having collars 16 which are secured to a shaft 18 journaled in the casting. The castings are 60 preferably provided with annular gaskets 15 to make a steam tight fit with the pistons, as shown in Figs. 1, 10, 11, 12 and 13. These gaskets may be pressed against the pistons by steam admitted through passages 17, as 65 shown in Figs. 12 and 13. On the outer circumference of each annular piston is a piston head 20 which fits the corresponding annular piston chamber. The piston heads of the two pistons are arranged at diametrically opposite points and swinging gates 22 are provided in each piston chamber for 70 co-operation therewith. These gates are secured to oscillatory trunnions 24 which carry adjustable counter-weights 25. Gaskets 23 75 are preferably provided in the casting to make a steam tight joint with the mounting of the gates. The gates on their ends are provided with gaskets 26 to engage the side walls of the piston chambers. Preferably 80 I provide seats 28 in the casting into which the swinging ends of the gates are adapted to fit, and the annular pistons are of slightly less diameter than the diameter of that portion of the casting which is provided with 85 these seats so that the pistons may rotate when the gates are seated. However, the end of the gate may be shaped to fit the curved surface of the casting, as shown in Fig. 6. At points close to but just ahead of the 90 swinging gates 22 live steam admission ports 30 open through the casting into the respective piston chambers. These admission ports lead from a steam chest 32 on the casting and receive steam from a supply pipe 34. For 95 opening and closing the admission ports oscillatory admission valves 36 are mounted in the casting and these valves have projecting stems 38 equipped with short arms 40 which are connected by links 42 with second arms 44 100 pivotally mounted on a projection from the casting. The pivotal connection between the arms 44 and links 42 have laterally projecting rollers 46 which work in endless profile cam channels 48 in cam wheels 50, one at 105 each end of the piston chambers and which are rigidly secured to the shaft 18. The cam wheels 50 have outer profile cam channels 52 in which work rollers 54 on short arms 56 connected to the trunnions 24 of 110 the swinging gates.

Each annular piston chamber has an ex-

haust port 58 located close to the underside of its respective gate 22 as shown in Fig. 2. The engagement of the rollers 54 with the cam grooves 52 will limit to some extent 5 oscillatory movement of the gates 22 but it is desirable to limit these movements more accurately. I therefore propose to provide the casting with stops 60 to limit the downward movement and with stops 62 to 10 limit the upper movement of the gates. These stops engage respectively the lower and the upper faces of the gates. The cam wheels 50 are set, the one, 180 degrees ahead of the other. The cam channels 52 are of 15 such form that they will hold gates 22 in their operative position shown in Fig. 2 throughout the greater portion of the rotation of the piston heads but will oscillate them into upward positions while the piston heads are moving past. The timing is 20 such that the gates will be returned to operative positions as quickly as possible after the piston heads have moved past the same. The cam channels 48 are of such form 25 that they will open the admission valves 36 as soon as the piston heads have passed the gates 22 and the latter have been oscillated back to operative position. Furthermore, the said cam channels are of such form that 30 the admission valves will be kept open during approximately the first ninety degrees of movement of the piston heads and then will cause said valves to close. Hence the piston heads will be driven by live steam 35 through about ninety degrees of their movement whereupon the admission valves will close and the confined steam will be allowed to act by expansion. Live steam will be admitted to one annular piston 40 chamber when the piston head in the other chamber is in the position indicated by dotted lines in Fig. 2 so that a very steady application of energy will be imparted to the power shaft 18. Exhaust ports 58 are 45 always open and hence the exhaust will occur as soon as the piston heads have passed their respective ports. The power shaft is mounted in bearings 64 as shown in Fig. 5 and this shaft at one end may have 50 a governor pulley 66 for connection with a suitable governor, and at its other end may have a large gear 68 meshing with a smaller gear 70 on a shaft 72 which may be a dynamo shaft.

55 The operation of my rotary engine will be readily understood from the above description and the advantages will be obvious. Steam will be applied to the rotary piston heads in a very effective manner and on account of the piston heads being one hundred eighty degrees apart the energy will be transmitted in a steady manner. Furthermore, as will be apparent from Fig. 1 of the drawings, the annular pistons are made 60 as thin as is practically consistent with suffi-

cient strength, and since they are of annular disk form they may be relatively thin as compared with the width of the piston chambers or the lateral dimension of the piston heads. This is of particular advantage in 70 an engine of this character in which live steam is admitted for only about ninety degrees of rotation of the piston heads. It will be apparent from an inspection of Fig. 2 that the pressure in the first quadrant of 75 the piston chambers is greater than it is in the other quadrants and that in the fourth quadrant where the steam is exhausted the pressure is very much less than it is in the first quadrant. If the thicknesses of the 80 annular pistons were equal to the width of the piston chambers it is evident that the pressure transmitted through the pistons to the shaft would be much greater on one side thereof than on the other and would affect the operation of the engine in an undesirable manner and in particular would cause binding of the shaft in its bearings. I obviate this undesirable result almost entirely by making the annular disk pistons as 85 thin as is practical. Furthermore, it is apparent that on account of the distance intervening between the shaft and the piston heads, a very effective leverage is obtained 90 and the torque on the shaft is much greater than it would be if the shaft and piston heads were not thus spaced.

I claim:

1. A rotary engine comprising a casting provided with an annular piston chamber, 100 a shaft extending through said casting centrally of said annular chamber, said casting having an annular passage extending from said shaft to said piston chamber, a rotary annular piston in said annular passage, said 105 piston being of less diameter than that of the portion of the casting which constitutes the interior wall of said piston chamber, a piston head on said annular piston working in said piston chamber, a gate mounted to 110 swing up and down in said piston chamber, the latter being provided in its interior wall with a seat for the swinging end of said gate, and a steam chest having an admission port 115 opening into said piston chamber adjacent one side of said gate, the piston chamber having an exhaust port adjacent the other side of said gate.

2. A rotary engine comprising a casting provided with two annular piston chambers, 120 a shaft extending through said casting centrally of said annular chambers, two rotary pistons secured to said shaft, a piston head on each of said rotary pistons operating in said annular chambers, the two piston heads 125 being arranged one hundred eighty degrees apart, a gate mounted to swing up and down in each of said annular chambers, a steam chest having two admission ports each opening into one of the annular chambers adja- 130

cent one side of the gate therein, each of said annular chambers having an exhaust port adjacent the other side of the gate, admission valves for opening and closing each 5 of said admission ports, two cam wheels secured to the aforesaid shaft one on each side of the casting, each of said cam wheels being provided with two cam channels one outside of the other in the face of said wheels, connections between one of said channels and admission valve for operating the latter and connections between the other of said channels and one of the gates for operating the latter, the inner cam channels being so 10 formed as to open the admission valves shortly after the piston heads have passed the same and to close said valves when the piston heads have moved substantially ninety degrees, and the outer cam channels being so formed as to open said gates just 15 before the arrival of the piston heads and to close said gates as soon as the piston heads have passed the same.

3. A rotary engine comprising a casting 25 provided with two annular piston chambers, a shaft extending through said casting centrally of said annular chambers, two rotary pistons secured to said shaft, a piston head on each of said rotary pistons working in

said annular chambers, the two piston heads 30 being arranged one hundred eighty degrees apart, a gate mounted to swing up and down in each of said annular chambers, a steam chest having two admission ports each opening into one of the annular chambers adjacent one side of the gate therein, each of said annular chambers having an exhaust port adjacent the other side of the gate, admission valves for opening and closing each 35 of said admission ports, two cam wheels secured to the aforesaid shaft one on each side of the casting, each of said cam wheels being provided with two cam channels one outside the other in the face thereof, an arm pivoted at one end to the casting, a roller 40 extending from the other end of said arm and lying in one of said cam channels, an arm extending from the stem of each of said admission valves, a link connecting said arms, a roller lying in the other of said cam channels and an arm upon one end of which said 45 roller is mounted, the other end of said arm being secured to the trunnion of one of said gates.

In testimony whereof I hereunto affix my 50 signature.

EVEN ULLAND.
